UNITED STATES PATENT OFFICE.

ANDREW CURTIS PREBLE, OF CHICAGO, ILLINOIS.

AUTOMATIC CHECK FOR ELEVATOR-DOORS.

1,102,799.

Specification of Letters Patent.

Patented July 7, 1914.

Application filed August 22, 1912. Serial No. 716,366.

To all whom it may concern:

Be it known that I, ANDREW CURTIS PREBLE, a citizen of the United States of America, and a resident of Chicago, in the county of Cook, State of Illinois, have invented certain new and useful Improvements in Automatic Checks for Elevator-Doors, of which the following is a specification.

10 This invention relates to that class of elevator well-doors, which are made in halves connected together so as to counter balance each other, and adapted to move simultaneously to and from each other in vertical directions in the closing and opening movements. And the present improvement has for its object to provide a simple and efficient means for automatically retarding the closing movement of the door sections, with 15 an avoidance of noise and damage to the parts, and with which the final closing movement of the sections can be easily effected, all as will hereinafter more fully appear.

20 In the accompanying drawings: Figure 1, is an elevation of a portion of an elevator door to which the present improvement is applied. Fig. 2, is an enlarged detail elevation of the present retarding mechanism, 25 the cylinder and controlling valve being shown in section. Fig. 3, is a detail vertical section of the same on line $x-x$, Fig. 2. Fig. 4, is a detail horizontal section on line $x'-x'$, Fig. 1. Fig. 5, is a detail vertical 30 section of a modification.

35 Similar reference numerals indicate like parts in the several views.

Referring to the drawings, 1 and 2 represent the respective upper and lower door 40 sections, having movement in vertical guides 3 within the elevator well, and disposed at the sides of the doorway. As usual in the present type of well doors, the sections 1 and 2 will be connected together so as to 45 counter balance by intermediate chains 4, which pass around overhead pulleys or sheaves 5, and are connected to lateral brackets 6 and 7 on the respective door sections, as illustrated in Fig. 1. And the connection of the chain 4 to the bracket 7 of the 50 lower door section 2 being preferably made by the usual elongated link or rod 8, for the purpose hereinafter stated.

55 9 is a cylinder secured vertically to the wall of the elevator well in adjacent relation to the above described rod 8. Said cyl-

inder has a lower open end, and an upper end closed by a head or cap 10, and from said upper end a passage or pipe 11 extends to the controlling valve hereinafter described.

60 12 is a piston moving in the bore of the cylinder 9, and having a depending piston rod 13 connected at its lower end to a cross-head 14, moving on suitable vertical guides 65 15, as shown. In the present construction the cross-head 14 is provided with a lateral arm 16 disposed in the path of the lateral bracket 7 of the lower door section 2, and adapted to receive positive upward movement 70 therefrom, as said door section moves upwardly in the closing movement of the door sections.

75 17 is a tappet or button attached to the rod 8 aforesaid, and adapted by engagement with aforesaid lateral arm 16, to effect the descent of the aforesaid piston and its accessories, when the same fail to return by gravity.

80 18 is an adjustable vent valve of any usual form, disposed in the head or cap 10 of the cylinder 9, and adapted to permit a retarded flow of air from such cylinder during the upward movement of the piston 12 in the same. The function of said valve is to prevent in a regulatable manner a rapid movement 85 of said piston and its accessories, in the above mentioned closing movement of the door sections.

90 19 is the casing of the main controlling valve of the present construction, preferably disposed below the open lower end of the cylinder 9, with its passage 20 connected to the upper end of the aforesaid cylinder 9, by the passage or pipe 11 before described. 95 And said passage also communicates with the open air, as illustrated in Fig. 2.

100 21 is the movable valve member of any ordinary construction, arranged in the valve casing 19, and formed with a transverse passage 22, adapted at the proper period in the operation of the mechanism, to register the passage 20 of the valve casing and the upper end of the cylinder 9, with the open air. The valve member 21 is also provided with 105 a pair of operating crank arms 23 and 24 arranged in right-angle relation, and disposed in vertical paths separated from each other a sufficient distance to permit independent operation of said arms by the individual means now to be described.

110 25 and 26 are individual tappet members

preferably secured to the piston rod 13 in an adjustable manner, and disposed in separated paths corresponding with the paths of the crank arms 23 and 24 above described and individual thereto. Said tappets are arranged at the desired vertical separation, and the arrangement is such that one will operate the movable valve member 21 to open the upper end of the cylinder 9 to the open air, and the other tappet member will operate said valve member to close said upper end of the cylinder.

In the operation of the present appliance, the opening movement of the door sections is effected in an unimpeded manner, in that no positive operative connection prevails between the door sections and the retarding appliance during such opening movement. In the closing movement of the door sections, however, the desired retardation of the speed of the door sections is attained in the following manner: With the valve member 21 in the closed position illustrated in Fig. 2, and as the lower door section 2 moves upwardly, the lateral bracket 7 carried thereon, comes in contact with the underside of the cross-head 14, after which the two parts move upwardly in unison, and such upward movement of the cross-head 14, through its attached piston rod 13, effects a compression of air in the upper portion of the cylinder 9, with the desired retardation of the parts, and the degree of such retardation is regulated as required by the adjustment of vent valve 18, heretofore described. As the piston 12 reaches a predetermined upward travel in the cylinder 9, the lower tappet 26 carried by the piston rod 13 of said piston, actuates the crank arm 23 of the movable valve member 21, to partially rotate said valve and bring its passage 22 in register with the passages 11 and 20 of the cylinder 9 and valve casing 19, and with the open air, to relieve the prevailing retardation, and thus permit a free final closing of the door sections without sudden jar or impact and with a certainty of complete closure.

With the described relief from retardation just described, the piston 12 and its accessories descend by gravity, and when the same near their full downward travel, the upper tappet 25, if the piston rod actuates the crank arm 24 of the movable valve member 21, to partially rotate the same, and move its passage 22, out of the above described register with the passages 11 and 20, and close the same to the open air, so that the appliance will be in condition for the next closing movement of the door sections. Should the piston 12 and its accessories fail to descend by gravity in the manner above stated, with the next opening movement of the door sections, the tappet or button 17 on the rod 8 is adapted to engage

against the top of the lateral bracket 16 and effect the described downward movement in a positive manner.

In the modification shown in Fig. 5, a slide valve 21' located at the upper end of the cylinder 9, is employed, and said valve is operatively connected in the manner shown to a pair of crank arms 23' and 24', similar in function and operation to the crank arms 23 and 24 before described. 70 75

Having thus fully described my said invention what I claim as new and desire to secure by Letters Patent, is:—

1. In a retarding mechanism for counterbalanced doors of elevator wells, the combination of a retarding cylinder having an outlet passage at one end, a piston and piston rod associated with said cylinder and provided with means for intermittent operative engagement with a moving part of a counterbalanced well door, a valve disposed in the aforesaid passage of the retarding cylinder, and means carried by said piston rod for operating said valve to relieve the cylinder of compression as the piston nears 90 the end of its stroke in one direction, substantially as set forth. 80 85 90

2. The combination of a retarding cylinder provided with a passage at one end, a valve controlling said passage and having a movable valve member provided with a pair of angularly disposed crank arms, a piston in said cylinder, a piston rod attached to said piston and having a pair of vertically separated tappets adapted for alternate operative engagement with aforesaid crank arms, and a cross-head carried by said piston rod and adapted for operative engagement with a moving part of a counterbalanced well door, substantially as set forth. 95 100 105

3. The combination of a retarding cylinder provided with a passage at one end, a valve controlling said passage and having a movable valve member provided with a pair of angularly disposed crank arms, a piston in said cylinder, a piston rod attached to said piston and having a pair of vertically separated tappets adapted for alternate operative engagement with aforesaid crank arms, and a cross-head carried by 110 115 120 125 130 said piston rod and adapted for intermittent operative engagement with the intermediate counterbalancing connection of a well door, substantially as set forth.

4. The combination of a retarding cylinder provided with a passage at one end, a valve controlling said passage, a vent valve in the same end of the cylinder, a piston in said cylinder, a piston rod attached to said piston and adapted for intermittent operative connection with said controlling valve, and a cross-head carried by said piston, and adapted for operative engagement with a moving part of a well door, substantially as set forth. 130

5. The combination of a retarding cylinder provided with a passage at one end, a valve controlling said passage, a piston in said cylinder, a piston rod attached to said piston and adapted for intermittent operative connection with said controlling valve, a cross-head carried by said piston rod and adapted for intermittent operative engagement with a tappet carried by the interme-

diate counter-balancing connection of an 10 elevator well door substantially as set forth.

Signed at Chicago, Illinois, this 20th day of August, 1912.

ANDREW CURTIS PREBLE.
